UNITED STATES PATENT OFFICE.

HENRY B. WHITE, OF TYLER, TEXAS.

DESIGN FOR A CHURN.

SPECIFICATION forming part of Design No. 35,274, dated November 5, 1901.

Application filed August 19, 1901. Serial No. 72,612. Term of patent 7 years.

To all whom it may concern:

Be it known that I, HENRY B. WHITE, a citizen of the United States, residing at Tyler, in the county of Smith and State of Texas, 5 have invented and produced a certain new and original Design for a Churn; and I do declare the following to be a full, clear, and exact description of the invention, such as will enable others skilled in the art to which 10 it appertains to make and use the same.

The invention relates to a design for a churn, and is illustrated in the accompanying drawing, in which the figure is a perspective view of the churn.

15 The leading or material features of the design consist of a cylindrical casing 1, closed at each end and provided at one end with a

handle 2, said casing having on its under side transverse triangular feet 3. A tubular extension 5 rises from the upper surface of the 20 casing and has a closure 6 and is located between the extremities of a bail 7.

Having thus described my invention, what I claim is—

The design for a churn substantially as 25 herein shown and described.

In testimony whereof I have hereunto set my hand in presence of two subscribing witnesses.

HENRY B. WHITE.
